(57) **CLAIM**

The ornamental design for a bipod as shown and described.

DESCRIPTION

FIG. 1 is a front, left, and top perspective view of a bipod, showing my design.

FIG. 2 is a rear, right, bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, left, and top perspective view of the bipod in one state.

FIG. 10 is another front, left, and top perspective view of the bipod in another state; and,

FIG. 11 is another front, left, and top perspective view of the bipod in yet another state.

The broken lines shown in the drawings are included for the purpose of illustrating portions of the bipod that form no part of the claimed design.

1 Claim, 11 Drawing Sheets
